UNITED STATES PATENT OFFICE.

ALFRED B. CHAPIN, OF BUFFALO, NEW YORK.

DEVICE FOR ATTACHING CARS TO MOVING TRAINS.

SPECIFICATION forming part of Letters Patent No. 225,272, dated March 9, 1880.

Application filed December 6, 1879.

To all whom it may concern:

Be it known that I, ALFRED BURWELL CHAPIN, of Buffalo, in the county of Erie and State of New York, have invented or made 5 certain Improvements in Devices for Attaching Stationary Cars to Railway-Trains while in Motion, of which the following is a specification.

This invention relates to attaching to the 10 main train while running at speed by any or every way or small station a car already loaded with freight, passengers, mails, &c., standing on a switch or side track by the side of the main track, which will be caught and 15 attached to the rear car of the train and carried along by devices hereinafter fully described, and, after being emptied of its freight, baggage, and passengers, is refilled with the parcels, passengers, &c., to be dropped at the 20 next station, and the car is uncoupled before arrival and run onto a side track at or near the station, and the one standing there to be caught by the passing train, and so on through the entire route, taking on and dropping cars 25 at any or all way-stations.

The object of this invention is to save greatly in the time of running trains now lost by taking on or off passengers, baggage, &c., at small stations, and to give stations now passed by 30 express or fast trains practically the advantages of large ones by instantaneously catching, taking along, and attaching a car while the passing train is in full motion. This will greatly shorten the time of running trains between distant points, and accommodate way- 35 business to a vastly greater extent than by the present system, and do away with the necessity of stopping at way-stations to deliver or take on passengers, mail-matter, baggage, express-packages, &c.

The invention consists in the arrangement of parts and in certain devices, all to be fully hereinafter specified.

In the drawings, Figure 1 is a plan of the 45 rear end of a passenger-car, the floor removed, showing a portion of the devices for catching and holding the supplementary car; Fig. 2, detail of brake and friction levers; Fig. 3, side elevation of the end of same car, showing friction-brakes, &c.; Fig. 4, end elevation, showing the drum and cable, slide, &c.; Figs. 5, 6,

7, detail views; Fig. 8, plan view of the front of the supplementary car, with devices for being drawn up to the rear car of the passing train; Figs. 9 and 10, details of double catch-hook; Fig. 11, side elevation, partly in section, showing the catch-hook arm and devices for operating the hook; Fig. 12, side elevation, in section, of the coupler; Figs. 13 and 14, details of same.

A represents the rear end or back of the last car of a passenger-train, and which will have a room partitioned off from the body of the car, leaving a passage-way from the rear platform to the rest of the car. In this room will be the 65 operating-levers, &c. The remainder of the space will be devoted to luggage, mail-bags, &c., to be put off at way-stations, and to receive those taken at the same from the attached cars as they are taken on. Beneath this room, 70 and under the hinder part of the car, is a drum, B, around which is wound in grooves a cable, of wire, rope, or chain, a, having a ball-weight, b, at its outer end. This drum revolves on a stationary screw-threaded axle, c, the ends 75 firmly fastened in a frame at the sides, so that the drum not only revolves, but also has a side motion on the screw-axle. This is to have the cable always drawn from the center of the rear end of the car. The thread of the screw and 80 the grooves in the drum in which the cable winds correspond for this purpose.

At the ends on the screw-axle c are loose friction-wheels C C, running on smooth bearings, always in the same position. Their peripheries are cut into a series of V-shaped grooves. Through the drum, and on opposite sides of the screw-axle parallel to it, are two rods, d d, their ends fastened to the friction-wheels C C. The drum, in moving, imparts, by these rods, 90 a similar motion to the friction-wheels; but the drum also moves sidewise on the screw as well as revolves. The holes in the drum through which these rods pass are sufficiently large to admit of the drum sliding back and forth. 95

To check the too quick movement of the drum, friction-brakes are applied to friction-wheels C, which consist of brake-blocks e e, behind the friction-wheels, and contained in a box. These blocks have a concave and grooved surface to fit the grooves in the friction-wheels, and are operated by the levers 1 2 3, attached 100

to rods *ff*, which unite under the floor, and are worked by the upright lever-handle *g*, which comes up in the room over the operating parts. When this brake is on it checks the running 5 of the drum and prevents the too swift paying out of the cable. Springs in connection with the brake-blocks keep them on.

Before a car is caught the brakes are withdrawn from the drum *B*. The springs would 10 put the brake on, providing the controlling lever *g* were not held back. This is done by a pawl, *a'*, attached to the lever, which, when the lever is drawn back, will catch in the notches of a ratchet-wheel, *R*, on the lever-frame. (See Fig. 2.) This wheel is attached 15 by a system of pulleys, 4 5 6 7, and belts to the friction-wheels *C*.

When the stationary car is caught the drum moves and the brake is put on automatically 20 by the notched wheel revolving and releasing the lever *g*.

In front of the friction-wheels *C* are friction-pulleys *h h*, which are grooved to mesh into corresponding grooves in the wheels *C C*. 25 They run on the ends of a long rod or shaft, *l''*, which moves forward and back in side slides, *n*, and with a wide band-wheel, *i*, or equivalent device, on the center, united by a belt to a band-wheel or pulley, *i'*, on the axle 30 of the car-truck. When this is thrown on by the lever-handle *g'* the pulleys *h* connect with the friction-pulleys *C*, revolve the drum, and wind up the cable, drawing the car up to the train. To prevent it winding too far as the 35 cars come together, the buffer on the opposite car strikes the spring-buffer *j*, on the inner end of which is a forked rod, *k*, which pushes against the frame-rod *l* of the friction-wheels *h h*, and throws them off from contact with the 40 drum friction-wheels *C C*.

An indicator, *D*, stands up in the room, attached to the lever-frame, which, by a series of pulleys and belts, 9 10 11 12 13, (the former, 9, attached to the friction-wheel *C*) moves an index, so that the brakeman can see how fast 45 the drum is revolving and the cable running out, and that the proper amount of brake-power is applied.

A set-screw, *m*, is arranged in the end of the 50 lever-frame, in front of the lever *g*, to prevent it going too far forward, and thus regulates the amount of pressure first applied through the friction-brakes *e e*.

A vertical coupling-pin, *o*, stands up on the 55 rear platform, its connection to be hereinafter explained.

On the rear end of this car, under the rear platform, are attached two frames or ways, *p p'*, as wide as the ends of the car, either or both 60 grooved, or one is grooved and the other with a rounded surface. In and on these slide right and left the frame or slide *E*, which carries the cable end held in a cross-head, *q*, provided with friction-rollers to lessen the friction 65 of the cable as it is pulled through. The cable also runs between two upright rollers, *r r*, (see Fig. 5,) behind the slide under the cen-

ter of the platform, so as to insure the cable winding in its proper grooves on the drum, especially when the railway-track is curved. 70 A small stop is fastened to the cable a short distance from the ball-weight, to prevent its being pulled through the cross-head. This cross-head *q* moves longitudinally on ways in the sliding frame *E*, and is carried to the extreme ends of the slide, or returned to the center by an endless belt or chain, *s*, attached each side of the cross-head *q*, and passing over grooved pulleys *t t* at each end of the slide and around another grooved pulley, *u*, on the 80 end of a thimble, *v*, which surrounds the vertical operating-rod *F*, where it passes through the platform. The upper part of the thimble is a flat disk, *q'*, having a double ratchet, *r'*, pivoted thereto. (See Fig. 6.) This engages 85 with a ratchet-wheel, *S'*, on the sleeve *G*, which, by turning the wheel *G'*, draws out the cross-head and cable. When there is a strain on the cable, if the cross-head is at the end of the slide, it will slide back to the center itself 90 gradually, and there remain while the cable pays out or is drawn in.

The devices for running out and returning the slide *E*, carrying the cable cross-head, are as follows: On the lower end of the operating-rod *F* is a toothed wheel, *w*, (see Fig. 7,) which meshes into a toothed rack, *s''*, on the back of the slide. The upper operating-wheel, *F'*, when turned one way, runs the slide out as far as necessary, and turned the reverse way 100 runs it back. It can be run out either side of the car, as described, carrying the cable end with it.

The description of the stationary or supplementary car is as follows: *H* in Fig. 8 is the 105 end of the stationary car, under which is arranged a semicircular way or guide, *I*, for an arm, *J*, to swing on, which has a double catch-hook, *K*, on its outer end. The inner end of this arm has a long rectangular opening, *x*, 110 which receives the end of a central post, *L*, leaving a space for the forward-and-back movement of the arm. There are also long side slots, *y y*, in the end of the arm with a pin, *z*, sliding therein, and which also passes 115 through the center post, *L*. A spring, *z'*, between the ends of post *L* and the back of the square part of the arm, takes off the shock when the arm is strongly pulled by the passing car *A*, and allows a necessary play of the 120 arm to overcome the inertia of the stationary car. This central post, *L*, revolves in a circular sleeve or frame strongly attached to the main timbers of the car. The arm *J* swings in a loose yoke, *N*, the upper part of the yoke 125 sliding on the guide *I*. When the arm is swung out it protrudes beyond the side of the car, so that the hook *K* will catch the ball-weight and cable end swung out from the rear side of the passing car *A*. This hook *K* is of 130 peculiar construction. The end of the arm is bifurcated longitudinally, and in this slit is set the double hook, which is of semicircular form on the outside, and is flush with the

- rounded end of the arm, the hooks protruding one from each side, something like barbs. A vertical pin, a' , confines it in the slit, said pin having a loose sleeve, b' , around it. (See Figs. 5 9 and 10.) Around the sleeve is a coiled spring, d'' , one end fastened to the inside of the end of the arm, which is made hollow and round to receive it, the other end having a screw or pin, c' , running longitudinally through it and the sleeve, and protruding into a longitudinal groove, d' , in the pin. A portion of the groove is closed by a stop, c' . (See Fig. 10.) The pin a' and hook K move together.
- When it is necessary to throw off the cable 15 from the hook on either side it is done as follows: The inner end of the hook-point has a slot, f' , (see Fig. 8,) which, when the hook is in place, is in line with the arm. In this slot f' a bolt or catch, h' , holds, which is operated 20 by a long rod, i''' , running along the top of the arm J , which has a short vertical pin, i'' , at its end. On the central post, L , is a pulley with an attached arm, j' , and around the pulley is a belt, k' , which runs around a pulley, l' , on 25 the vertical rod m' . (See Figs. 8, 11, and 12.) When the wheel m'' is worked it revolves the pulley-arm j' , which strikes against the vertical pin i'' and pushes the long rod outward, withdrawing the catch h' , thereby releasing 30 the hook K , which flies outward either side that the cable may be caught in, and releases the cable, according to which side of the car the hooked arm is swung out from. The pulley-arm j' on the central post, L , is swung 35 round either way. The vertical pin i'' , rod i''' , and bolt h' are returned to place by a spring, n' .
- On each side of the arm J , opposite the hooks K , are wings $o' o'$, to guide the cable and ball in place and aid in catching it.
- 40 When the hook is released by the bolt h' the springs d'' in the end of the arm J throw it back in place, each acting independently of the other, one spring acting when the hook is pulled out at one side, and the other spring 45 acting only when the hook is pulled out at the other side, otherwise one of the springs would be pressed backward and broken by uncoiling it.
- The devices and operation to prevent uncoiling are as follows: A vertical projection, e'' , is fastened to or forms part of the sleeves $b' b'$, which sets against a stop, f'' , on the box of the springs to prevent the springs moving farther. The hook, for example, is 55 pulled out at the right side of the arm to release the cable; then the lower spring operates the lower screw-pin c' , engaging against the stop c' in the groove of the central pin, a' , carries around the sleeve b' , coiling the spring, 60 which, when the cable is released, springs the hook back into place. The upper screw-pin c' and sleeve remain stationary by reason of the longitudinal groove in the central pin allowing the upper screw-pin to remain therein, 65 while the central pin, a' , revolves loosely, carrying its own stop away from that screw-pin until thrown back by the lower spring, when
- it engages against the screw-pin ready for the action of the hook if drawn out at the left-hand side. If so, it operates the upper spring 70 and sleeve precisely as described for the lower ones.
- The construction of the upper and lower parts are similar, only having a reversed action. By this means it is impossible to uncoil 75 or break either spring.
- When the car stands on a side-track that is on an incline grade it is obvious that the car-brakes must be set to prevent its moving. When the passing car catches this stationary 80 car an automatic arrangement throws off the brakes by the swinging around of the hooked arm J . This is accomplished as follows: To one side of the surface of the post L , which swings with the arm J , is pivoted a long lever, 85 14. The other end is pivoted to a short lever, 15, whose other end is fastened to a disk, q' , above the floor of the car. On the top of this disk is a pivoted dog, r'' , that catches into a ratchet wheel, s''' , attached to the sleeve O 90 and worked by the brake-wheel O' . The dog holds the brake when set. A pin, w' , is set in a hole in the disk just in front of the dog, when the brakes are to be thrown off by the movement of the arm J . The swinging of this arm 95 from the side to the center moves the disk around sufficiently to release the dog r' from the ratchet-wheel s''' , and throws off the brakes, allowing the immediate movement of the car.
- On the platform is a coupling-arm, P , swinging 100 around the sleeve of the brake-rod, the inner end attached to a hollow box, P' , which encircles the vertical brake-rod and sleeve, the arm swinging horizontally in one direction, and thrown back into position by a coiled 105 spring, v' , inside the box P' .
- The coupler on the outer end of this swinging coupling-arm is a hollow circular box, P'' , in which is pivoted by a central pin, w' , a catch-hook, y' , (see Figs. 13 and 14,) with one 110 protruding hooking-point. A coiled spring, v'' , throws the hook back into position after being pulled out. This hook engages with the upright coupling-pin o on the car A , before referred to. As the cars meet, by the car H 115 being drawn to car A by the cable winding up, the outer rounded edge of the coupler-hook y' strikes against the pin o of the opposite car, pushing the coupler and arm side-wise until the pin slides over the hook y' , and 120 the spring v' throwing the coupler back into position and holding the cars together.
- The uncoupling is accomplished as follows: The back end, y'' , of the hook y' has a slot, y''' , therein, in which a bolt or catch, z'' , sets. 125 A bent lever, Q , is attached by one end to a projection of the coupler-box P'' , and at a short distance from this is pivoted into the catch-bolt z'' . Between this and the coupler-arm, and around the upper part of the catch-rod, is a coiled spring, w''' . By the brakeman pressing his foot on this lever the catch is pressed down and out of the slot y''' of the catch-hook, which, thus released, flies out and 130

disconnects from the pin o , and the cars are at once separated. The spring v'' returns the hook y' to its place, the inner end, y'' , with the slot y''' , catching the bolt z'' , which slips into the slot y'' .

5 The operation of the whole device is as follows: The car H stands at a way-station on a side track, which, by a switch, runs into the main track. The car is previously loaded, and 10 the arm and hook J swung out on the side to the main track. The car A of the moving train has previously thrown out from the rear of the back car the slide carrying the cross-head and cable with the weighted ball. This 15 slide will be arranged to stand just above the hooked arm J , so that the cable-ball will be caught by the hook and there held. The cable at once pays out on the drum B , the friction-brakes are set hard against the friction-wheels 20 $C C$, thereby causing the car to acquire a small portion of the velocity of the train, and the hooked arm, swinging round from the side toward the center of the car H , throws off automatically the brakes that were set to hold 25 the car H on the side track till caught by the passing train. As the car H gathers momentum and gradually acquires the speed of the train, having previously run from the switch to the main track, and the drum ceased to 30 move, by which time the car H has acquired the full motion of the train, the friction-brakes on the drum are thrown off and the friction-brake pulleys $h h$ applied to the front of the drum friction-wheels $C C$, and the movement 35 acquired by the band and band-wheels, operated by the axle of the car-truck, winds up the cable and draws the car H up to the car A , when the automatic coupler engages with the pin o and holds the two together. 40 The passengers, mails, baggage, &c., are now transferred from car H to the car A , and another transfer back of persons and packages that are to be left at the next station. Previous 45 to arrival there the brakeman presses down the lever Q and disconnects the two cars, the car H switching onto a side track, and is stopped at the station, while the main train passes by and picks up another supplementary car there, and so on the whole route.

50 Both ends of the stationary car may be constructed alike, if desired; but only one end of the rear car of a train need be furnished with the drum and cable, &c. The arm and hook can be swung out either side of the car H , and 55 the cable and weight slid out from either side of the passing car.

It is obvious that the devices on the moving car can be put on the stationary car, and vice versa, if found desirable.

60 I claim—

1. The drum and cable to be operated from a railway-car of a moving train, in connection with an arm or hook, $J K$, or their equivalents, attached to a stationary car, H , for the purpose of catching said cable, and with suitable brakes to act on said drum, substantially as and for the purpose hereinbefore specified.

2. The frames $p p'$, slide E , cross-head q , situated at the end of the car A , and in combination with the drum B and cable $a b$, all substantially as and for the purpose specified. 70

3. In combination with the slide E , frames $p p'$, and cross-head q , the devices for operating the same, consisting of the grooved pulleys $t t$ u , rope or belt s , friction-rollers $r r$, rod F , operated by wheel F' , sleeve G , and wheel G' , thimble v , toothed wheel w , rack s'' , disk q' , with ratchet-wheel S and pivoted ratchet r' , all substantially as and for the purpose specified. 75

4. In connection with a railway-car, the combination of the cable-drum B , moving on screw-axle c , drum-rods $d d$, and grooved friction-wheels $C C$, running on smooth bearings at ends of screw-axle c , all substantially for the purpose specified. 80

5. In combination with the friction-wheels $C C$, the grooved brake-blocks $e e$, operated by the levers $1 2 3$, rod f , and lever-handle g , all substantially as and for the purpose specified. 85

6. In combination with the brake-blocks $e e$ and friction-wheels $C C$, the automatic devices for throwing on the brakes connected with the lever g , consisting of pulleys $4 5 6 7$ and belts, ratchet-wheel R , and pawl a'' , (on lever g), all arranged and operating substantially as hereinbefore specified. 90

7. In combination with friction-wheels $C C$, the devices for winding up the cable a on the drum B , consisting of the grooved friction-wheels $h h$, shaft l'' , the ends of the latter moving forward and back in side slides, n , the band-wheels $i i'$, band-frame rod l , and attached lever g' , all substantially as specified. 95

8. In combination with the spring-buffer j , the buffer-rod k , connected thereto, and by which the pressure on the buffer j acts on the frame-rod l , and automatically throws off the friction-wheels $h h$ from the drum friction-wheels $C C$, substantially as and for the purpose hereinbefore specified. 100

9. The indicator D , operated by the pulleys $9 10 11 12 13$ and belts, in combination with the friction-wheels $C C$, substantially as specified. 105

10. In combination with the car H , the hook-arm J , swinging either way on the central post, L , and ways I , and the outer end provided with a catch-hook, K , substantially as specified. 110

11. The catch-hook consisting of the hook K , the central pin, a' , with slots d' , stops e' , sleeves b' , screw-pins c' , one end setting in the groove d' , the springs d'' , the projections e'' , and stops f'' , all in combination with the bifurcated end of the arm J , in which the hook operates, as and for the purpose specified. 115

12. In combination with the swinging arm J , the double catch-hook K , moving on or with the central pin, a' , and returned to position, with or without a spring or springs, and operating substantially as specified. 120

13. In combination with the hook K , the devices for unfastening it, consisting of the catch or bolt h' , jointed rod i''' , pin i'' , pulley and 125

arm j' , belt k , pulley l' , operating-rod and wheel $m' m''$, all substantially as and for the purpose specified.

14. The devices for automatically throwing off the car-brake when the supplementary car H is started, consisting of the rod 14, pivoted at one end to the central post, L , and at the other to lever 15, the disk q' , dog r'' , ratchet-wheel s''' , pin u'' , and sleeve and brake-wheel O to O' , in combination with the usual brakes of a car-truck, the central post, L , and arm J , all substantially as and for the purpose specified.

15. The coupler consisting of the swinging arm P , boxes $P' P''$, bolt-lever Q , spring-bolt $z'' w'''$, hook $y' y'' y'''$, springs v' and v'' , and pin w' , all substantially as and for the purpose specified. 15

In witness whereof I have hereunto signed my name in the presence of two subscribing witnesses.

A. B. CHAPIN.
